UNITED STATES PATENT OFFICE.

WILLIAM C. PEET, OF NEW YORK, N. Y., ASSIGNOR TO THE J. L. MOTT IRON WORKS, OF SAME PLACE.

DESIGN FOR A LEG FOR BATH-TUBS.

SPECIFICATION forming part of Design No. 23,351, dated June 12, 1894.

Application filed May 7, 1894. Serial No. 510,405. Term of patent 14 years.

To all whom it may concern:

Be it known that I, WILLIAM C. PEET, a citizen of the United States, residing in the city, county, and State of New York, have invented a Design for a Leg for Bath-Tubs or Similar Articles, of which the following is a specification.

The leading feature of this design consists in the representation of an animal's paw at the lower end and a spreading leaflet trefoil ornament at the upper part at the side of the article supported by the leg.

In the drawings:—Figure 1. is a front view and Fig. 2. is a side view of the design for the leg of a bath tub or other article.

The design of the portion A. represents an animal's paw, and the central leaflet B. and side leaflets C. form a trefoil ornament.

I claim—

The design of the leg for a bath tub or similar article substantially as described and represented.

Signed by me this 3d day of May, 1894.

WILLIAM C. PEET.
